UNITED STATES PATENT OFFICE.

IRA E. STUMP, OF CLEVELAND, OHIO, ASSIGNOR OF ONE-HALF TO
HENRY J. POPPENHAGEN, OF CLEVELAND, OHIO.

WRENCH.

SPECIFICATION forming part of Letters Patent No. 768,703, dated August 30, 1904.

Application filed February 4, 1904. Serial No. 192,017. (No model.)

To all whom it may concern:

Be it known that I, IRA E. STUMP, a citizen of the United States, residing at Cleveland, in the county of Cuyahoga and State of Ohio, have 5 invented new and useful Improvements in Wrenches, of which the following is a specification.

This invention relates particularly to wrenches having an adjustable jaw slidable on 10 the shank of the fixed jaw, and is especially directed to the means for adjusting the said movable jaw and for holding it in position as set, as will more fully hereinafter appear.

In the accompanying drawings, Figure 1 is a 15 perspective view of the wrench. Fig. 2 is a longitudinal section thereof.

Referring specifically to the drawings, 6 indicates the fixed jaw, and 7 the shank extending therefrom, which shank terminates in a 20 handle 8. The back of the shank is knurled or toothed, as at 9.

The movable jaw is indicated at 10, the back side or edge thereof being grooved between two side pieces 11 to take the shank 7, 25 the front edge of which is preferably rounded, as indicated at 12.

Pivoted at 13 to the movable jaw 10 are a 30 pair of bent levers 14, which are located on both sides of the movable jaw and which swing in a plane parallel to the length of the shank.

One arm of these levers extends backwardly beyond the toothed side of the shank, where it carries a knurled or toothed block 15 by a pivotal connection, (shown at 16.) The teeth 35 or roughened face of the block is arranged to engage the teeth or knurls 9. The levers 14 are bent to substantially a right angle and at the end of the other arms thereof carry a thumb-piece, (indicated at 17,) by which the 40 levers are manipulated. This thumb-piece has the form of a piece of metal bent around a pivot-pin 18, extending between the levers, and the inner end of said piece bears against the front edge of the movable jaw, as indicated at 19. The outer end or arm, to which

the thumb-pressure is applied, is of greater length than and extends beyond the arm 19, so that a leverage is produced which when the thumb-piece is pressed turns the thumb-piece on the arm 19 as a pivot and lifts or throws 50 the pivot 18 outwardly or forwardly, which lifts the block 15 upwardly or backwardly and disengages the same from the teeth 9. A flat spring 20 is attached at one end to the movable jaw and presses at the other end 55 against the arm 19, normally causing the levers 14 to hold the block 15 in engagement with the shank, the release being effected in opposition to the spring in the manner above indicated.

The strength of the grip of the wrench does not depend on the toothed or knurled surfaces, but is effected principally by the peculiar leverage incident to the arrangement. Pressure on the movable jaw 10 lengthwise of the 65 shank, such as would be produced in straining a nut, causes or tends to cause by the pivotal connection 13 an inward pressure on the block 15. The levers 14 naturally tend under such pressure to swing inwardly, with the result 70 that the harder the pressure the tighter the block is gripped to the back edge of the shank. The adjustment is quick, since pressure on the thumb-piece instantly disengages the block and shank and allows the adjustable jaw to be 75 moved at once to the place desired. It is to be noticed that the shank has a slight taper from the handle to the fixed jaw, so that when straining a nut the grip tightens—that is, the grip of the movable jaw on the shank.

What I claim as new, and desire to secure by Letters Patent, is—

In a wrench, the combination with a shank having at the end thereof a fixed jaw, the back of the shank being notched, of an inner movable jaw slidable on the shank, levers pivoted on opposite sides of the movable jaw, a block carried by the levers behind the shank and engageable with the notches therein, the engagement of the block with the shank being 85 90

nearer the fixed jaw than the pivotal connection of the lever with the movable jaw, a pin extending between the ends of the levers, and a thumb-lever carried by said pin and having 5 its fulcrum on the movable jaw, to operate said levers, substantially as described.

In testimony whereof I have signed my name

to this specification in the presence of two subscribing witnesses.

IRA E. STUMP.
